STEAM GENERATING APPARATUS

Perry Arant, Alhambra, Calif., assignor to Clayton Manufacturing Company, Alhambra, Calif., a corporation of California

Original application August 6, 1946, Serial No. 688,720. Divided and this application August 6, 1946, Serial No. 688,721.

13 Claims. (Cl. 122—250)

1

The present invention relates to steam generating apparatus, and more particularly to novel combustion chamber lining and jacket cooling means for such apparatus.

The principal object of the invention is to provide a combustion chamber lining for steam generating apparatus which will satisfactorily withstand excessively high operating temperatures for unusually long periods of time.

Another object of the invention is to provide a combustion chamber lining means for steam generating apparatus which will eliminate the usual great thickness of insulating material normally required to satisfactorily resist the great heat generated by the combustion of fuel within the combustion chamber, thereby enabling the apparatus to be made more compact.

A further object of the invention is to provide steam generating apparatus including means for maintaining a low jacket temperature.

A still further object of the invention is to provide steam generating apparatus which will not cause undue heating of the boiler room or chamber in which it is installed.

Other objects and features of the invention will be apparent from the following description taken in conjunction with the accompanying drawings, in which:

Fig. 1 is a longitudinal sectional view through a steam generating apparatus embodying the present novel heating coil, combustion chamber lining, and jacket cooling construction;

Fig. 2 is a sectional view taken on the line 2—2 of Fig. 1;

Fig. 3 is a sectional view on the line 3—3 of Fig. 1 and particularly illustrating the construction of the base of the apparatus and the air deflecting means for maintaining a low jacket temperature;

Fig. 4 is an enlarged fragmentary sectional view taken on the line 4—4 of Fig. 3, and illustrating the manner in which the shell surrounding the heating coil is assembled with the base and one of the legs of the apparatus;

Fig. 5 is an enlarged fragmentary sectional view taken on the line 5—5 of Fig. 3, and illustrating the means employed for supporting the helical water wall coil perpendicular with respect to the base of the apparatus; and

Fig. 6 is an enlarged fragmentary sectional view taken on the line 6—6 of Fig. 3, and illustrating one of the apertures which establish communication between the annular air space in the base and the annular air space in the jacket, for facilitating "scooping" of the moving air from the base into the jacket air space.

2

Referring now to Figs. 1 to 6, inclusive, of the drawings, the numeral 1 generally identifies the steam generating apparatus which includes legs 2 supporting a housing comprising a base 3, an intermediate jacket section 4, and a top section 5.

The base 3 includes a lower horizontal, circular bottom wall 6 having a peripheral flange 7 welded to the lower end of an outer ring 8. The base 3 further includes an upper horizontal, circular wall 9 provided with a flange 10 at its outer periphery welded to the lower end of an intermediate ring 11 arranged concentric with the ring 8. The walls 6 and 9 are spaced apart to provide an air space 12 therebetween. A plurality of air deflecting baffles 13 are spot welded to the underside of the wall 9 and serve as spacing means between the walls 9 and 6. An air supply duct 14 is disposed below the wall 6 and secured thereto in any desired manner. A blower 15 forces air under pressure into the duct 14. The wall 6 is provided with a central air inlet opening 16 communicating with the air supply duct 14. The duct 14 is preferably designed to deliver air to the opening 16 moving at high velocity in a counterclockwise, spiral or volute path and may be constructed, for example, in the manner disclosed in Kerrick Patent 2,284,906. The wall 9 is provided with an opening 17 arranged concentric with the opening 16 of the wall 6, but of smaller diameter, and has a bushing 18 mounted therein. The bushing 18 has a passageway 19 which establishes communication between the air supply duct 14 and a combustion chamber 20 within the jacket 4 above the base 3. The passage in the bushing 18 is smaller than the opening 16 and therefore a portion of the air supplied through the duct 14 is deflected laterally or outwardly by the wall 9 into the space 12 between the walls 6 and 9 to maintain a low jacket temperature, as will be explained later.

It will be understood, of course, that a forced draft is maintained in the steam generating apparatus 1 and to this end air is forced into the supply duct 14 by the blower 15 which is capable of supplying a greater volume of air than is required for complete combustion of the fuel, with sufficient excess for diversion into the air space 12 for jacket cooling.

An inner ring 22 is preferably welded at its lower end to the upper side of the wall 9 and is arranged concentric with the rings 8 and 11. The ring 22 is considerably smaller than the ring 11 providing a space 23 between the outer periphery thereof and the inner periphery of the ring 11. Suitable refractory material 24 is disposed between the bushing 18 and the ring 22 and is sup-

ported by the wall 9. The upper surface 25 of the refractory material 24 is inclined downwardly toward the bushing 18, as best shown in Fig. 1.

The air inlet duct 14 supports a burner device 29 including a pair of nozzles 27 for atomizing the fuel introduced into the combustion chamber 20. A pipe 28 is connected to the burner 26 for supplying fuel thereto, and electrode means 29 is arranged to initiate ignition of the fuel.

The steam generating apparatus 1 includes a novel heating coil construction generally identified by the numeral 35. The heating coil 35 includes a preheater section 36, a water wall section 37 and a generating section 38, arranged in series flow, but with the generating section 38 disposed below the preheater section 36 and within the upper end portion of the water wall section 37. The preheater section 36 has an inlet 39 and may include any suitable number of spirally wound pancake coil sections 40 arranged in superposed relation. In one operative form of the invention, the preheater section 36 includes, for example, eight individually wound pancake coils 40, as illustrated in Fig. 1, and the inner end or outlet 41 of the uppermost pancake coil 40 is welded to the inner end or inlet 42 of the second pancake coil 40, and the outlet 43 of said second pancake coil is welded to the inlet 44 of the third pancake coil 40, and so on, throughout the height of the preheater section 36, with the result that the pancake coils 40 are interconnected in series and the outlet of the preheater section 36 is located at the outer end 45 of the lowermost pancake coil 40.

The water wall section 37 consists of a double wound helical coil preferably made of two predetermined lengths of pipe 50 and 51 interconnected at one end in the finished coil by a return bend 52. The method of winding the double coil 37 is set out in full in my copending application, Serial No. 688,720, filed of even date herewith, and of which the present application is a division. The end 53 of the pipe 50, remote from the return bend 52, is welded to the outlet end 45 of the preheater section 36, and the corresponding end 54 of the pipe 51 is welded to the inlet 55 of the generating section 38. The double winding of the water wall section 37 provides a construction in which the fluid flows downwardly for the full length of the pipe 50, or in a direction counter to that of the path of travel of the combustion gases, and then reverses flow at the return bend 52 and flows upwardly in the pipe 51 toward its end 54 in the same general direction as the travel of the combustion gases; the result being that the fluid flow in any two adjacent turns of the water wall section 37 occurs in opposite directions, as indicated by the arrows in Fig. 1. In the present construction, the water wall 37 is illustrated as having, for example, about sixteen complete turns disposed vertically one above the other, with the upper half, or first eight turns, in substantially abutting relation and with the remaining eight turns spaced about $\frac{1}{2}$ inch apart, and maintained in such spaced relation by clips 56 welded to or inserted between adjacent turns. The object of the different spacing of the turns of the water wall section 37 will be explained later.

The generating section 38 is shown in Fig. 1 as consisting, for example, of five individual pancake coils 60 arranged so that the inner end 61 of the uppermost or first pancake coil 60 is welded directly to the inner end 62 of the lowermost or fifth pancake coil 60. The outer

end 63 of the lowermost pancake coil 60 is welded to the outer end 64 of the next adjacent, or fourth, pancake coil 60, the inner end 65 of the fourth pancake coil is welded to the inner end 66 of the third pancake coil, the outer end 67 of the third pancake coil is welded to the outer end 68 of the second pancake coil, and the inner end 69 of the second pancake coil is welded to one end 70 of the discharge pipe 71.

Thus, the fluid discharged from the upper end 54 of the water wall section 37 enters the first pancake coil 60 of the generating section 38 and flows therefrom to the lowermost pancake coil 60 and then upwardly through the fourth, third and second pancake coils and into the discharge pipe 71, by flowing in the same general direction as the travel of the combustion gases.

The pancake coils 60 are slightly spaced apart and are held in such spaced relation by clips 72 welded or otherwise secured to the outermost coils thereof. A baffle plate 73 is arranged in the generating section between the second and third pancake coils 60, the fourth and fifth pancake coils 60 and below the fifth pancake coil 60 to prevent the direct passage of combustion gases through the core 74 formed at the central portion of the generating section 38. Soot blowers (not shown) are preferably disposed between the pancake coils 60 of the preheater section 36.

A shell 116, formed from a rolled sheet of metal, encloses the coil 37 and its longitudinal edges are in abutment, and a strip 118 (Fig. 2) is welded to the shell 116 at the abutting portions thereof to hold the same in cylindrical form. A plurality of angle brackets 119 (Fig. 4) is welded to the shell 116 adjacent the lower end thereof.

The lowermost turn of the coil 37, of course, is arranged on a helix and in order to support the same vertically, a plurality of strips or feet 117 (Figs. 3 and 5) of different vertical height are welded to the lower side of said turn.

The shell 116 is of insufficient length to enclose the preheater section 36 and, hence, a second shell 120 (Fig. 1), having the main inlet 39 and the discharge pipe 71 extending therethrough, is arranged in telescoping relation with the shell 116 and is welded at its lower end 121 to the upper end of the shell 116.

A crossbar 122 (Fig. 2) extends across the upper portion of the shell 120 and the opposite ends thereof are secured to said shell by brackets 123 bolted to said crossbar and shell, respectively. A second bar 124 arranged at right angles to the crossbar 122 has one end welded to the adjacent side of the crossbar 122 and its other end fastened to the shell 120 by a bracket 126 bolted to both said bar and shell. Another bar 127 has one end thereof welded to the opposite side of the crossbar 122 and its opposite end is secured by a bracket 128 and suitable bolts to the shell 116. A tie bar 129 (Fig. 1) bridges the crossbar 122 and overlies the adjacent end portions of the bars 124 and 127 and is welded along its lower edges to all of said bars to stiffen the same and form a rigid bridge across the crossbar 122. A hook member 130 has a shank 131 disposed at the point of juncture of the bars 122 and 127 and is welded thereto and to the tie bar 129. The lower edges of the bars 122, 124 and 127 are preferably welded

70 to the upper pancake coil section 40 of the preheater section 36. The hook 130 thus provides a convenient device for handling the entire shell and coil assembly by means of a crane (not shown). After the assembly of the coil and shell 75 has been completed, as above described, the same

is subjected to a conventional heat treatment to relieve all stresses and strains therein.

After the coil assembly has been heat treated, a stainless steel cylindrical sheet liner 132 (Fig. 1) is inserted within the lower portion of the water wall section 37. The height of the liner 132 is preferably such that it extends upwardly into the region of the generating coil section 38. The upper end of the liner 132 is curved inwardly, as indicated at 133, to facilitate such insertion. The liner 132 is preferably made of stainless steel, that is, a chrome-nickel steel, commercially known as 18-8 stainless steel, although other stainless steels of different ratio of chrome to nickel have been found to be satisfactory. Ordinary sheet iron may also be used in making the liner 132, but the life of such a liner is relatively short and stainless steel is preferred because it eliminates the replacement problem.

The thickness of the stainless steel liner 132 is of the order of .04 inch to .14 inch and preferably .06 inch. The heavier gauge material is capable of slightly deforming out of round individual turns of the water wall section 37 so that good heat transfer contact can be maintained between the outer surface of the liner 132 and the inner surface of all of the coil turns. The liner 132 is made by rolling a flat sheet of stainless steel into cylindrical form and then welding or otherwise securing the vertical edges together. Afterward, one end is rolled to turn the same inwardly to provide the rounded edge 133, previously referred to.

The external diameter of the liner 132 is dependent upon the internal diameter of the water wall section 37 and their relative rates of thermal expansion. In this connection, the liner 132 is made of such external diameter that it can be readily slipped into the water wall section 37 with some slight clearance, the clearance being such that it will subsequently be eliminated under normal combustion temperatures by expansion of the liner 132 into positive contact with the innermost surfaces of the water wall section 37.

In one operative example of a 50 horsepower unit, the internal diameter of the turns of the water wall section 37 was 23 $\frac{1}{8}$ inches and the outer diameter of the liner 132 was 22 $\frac{7}{8}$ inches, thus allowing $\frac{1}{4}$ of an inch total clearance for expansion. The internal diameter of the turns of the water wall section 37 is held to a desired dimension by the expedient of employing the shell 116 of predetermined internal diameter and the step of allowing the helical coils formed from the pipes 50 and 51 to only partially unwind after the shell 116 has been slipped thereover, as described herein in connection with the method of making said water wall section.

No special heat treatment is given to the stainless steel liner 132; it is simply inserted within the water wall section 37 after the coil assembly 35 has been stress-relieved. In operation, the liner 132 will expand into positive engagement with the surrounding turns of the water wall section 37, and in some instances may bulge slightly outwardly between adjacent turns, as illustrated to an exaggerated degree in Fig. 4. Normally, however, the liner 132 will contract upon cooling, so that it can be readily removed from the coil 37. After the unit has been in operation for a period of time, the coil 37 and the liner 132 take a more or less permanent set, in contact, as a result of the loss of elasticity due to repeated heating and cooling.

Continuing now with the description of the

remainder of the steam generating unit 1, four inverted U-shaped members 135 (Figs. 3 and 4) are disposed in the space 23 and their end edges are respectively welded to the rings 11 and 22. The U-shaped members 135 are arranged to serve as supports for the feet 117 at the lower end of the water wall section 37. The members 135 are also vertically aligned with the brackets 119 secured to the lower end of the shell 116. Bolts 136 project through the brackets 119, the horizontal wall of the U-shaped members 135, through openings in the bottom walls 9 and 6 and through an opening in an inwardly extending flange of the supporting legs 2, as best illustrated by way of example in Fig. 4, for securing the shell 116 in assembled relation with the base 3 and legs 2. The legs 2 are additionally secured to the base 3 by bolts 138 which extend through the ring 6 and into a reinforcing strip 139 (Fig. 4) engaging the inner surface of the ring 8.

Layers 140 and 141 of heat insulating material surround the shells 116 and 120 to minimize heat losses. A cap member 142 is disposed above the upper end of the shell 120 and is secured thereto in any suitable manner. The cap 142 has a central flue opening 143 and a sleeve 144 provided with openings 145 surrounds the flue opening 143. A layer of insulating material 146 is disposed outwardly of the sleeve 144 and overlies the upper surface of the cap 142, as shown.

The outer ring 8 of the base 3 has an outwardly extending flange 147 (Figs. 1 and 3) at its upper end, and the intermediate ring 11 has an outwardly projecting flange 148 which overlies and engages the flange 147. The lower end of the jacket section 4 has an outwardly extending flange 149 that rests upon the flange 148. The flanges 147, 148 and 149 may be bolted or welded together, as desired. The jacket 4 has a lining 40 of insulating material 150 which is arranged outwardly of the insulating material 141 to provide an annular air space 151 completely surrounding the insulated heating coil assembly.

The upper end of the jacket 4 has an outwardly extending flange 152 (Fig. 1) and the cap 5 has a similar flange 153 resting upon the flange 152. The flanges 152 and 153 may be bolted or welded together, as desired. The sleeve 144 projects into an opening 154 in the cap 5 so that an air space 50 155, communicating with the annular air space 151, is formed between the inner surface of said cap and the insulating material 146, the openings 145 providing communication between the air space 155 and the flue opening 143.

The flange 148 of the intermediate ring 11 contains a plurality of circumferentially spaced apertures 156 which have their edges bent, as indicated in Fig. 6, to form air scoops facing in a counterclockwise direction. These apertures 60 establish communication between the annular air space 151 in the jacket 4 and an annular air space 158 between the rings 8 and 11. Accordingly, air travelling in a counterclockwise, spiral path and introduced through the opening 16 into the air space 21 in the base 3 is deflected outwardly by the overlying portion of the wall 9 and the baffles 12 into the air space 158, and is scooped by the leading edges of the apertures 156, into the annular jacket air space 151 to remove any heat that has passed through the insulating layers 141-142, whereby to maintain the temperature of the jacket 4 at a minimum to prevent undue heating of the boiler room or chamber in which the steam generating unit 1 is installed. The 70 heated air forced out of the air space 151 passes

7
through the air space 155, openings 145 and is exhausted into a stack 159 surrounding the opening 154 in the cover 5.

It will be noted from Fig. 1 that the lower end of the liner 132 rests upon the upper surface 25 of the refractory material 24. The object of such arrangement is to provide a seal at the lower end of the liner 132 that will keep the fuel confined within the combustion chamber 20 so that it cannot leak into the space occupied by the water wall section 37 and the insulating material 140, 141 and 150. The seal is particularly important when gaseous fuels are used inasmuch as under such conditions it would be highly undesirable to have combustible material leak out of the combustion chamber into the air space 151 surrounding the coil 35 in view of the fire hazard which it would present. In the case of liquid fuels, such as oil, the same might also constitute a fire hazard, but oil presents the further objection in that it would be absorbed by the insulating material and decrease the efficiency thereof.

In actual operation, operating temperatures in steam generating units of the character comprising the present invention range from 2500° F. to 2900° F. depending upon the size of the unit. The highest temperature which present-day refractory materials are capable of withstanding is about 2900 to 3000° F. maximum, which does not leave any margin of temperature resistance to resist direct flame impingement causing heating above the maximum and which most generally causes refractory failure at the point of flame impingement. The present invention eliminates the use of refractory material in the side walls of the combustion chamber by incorporating a water wall section 37 and a stainless steel liner 132, which was unexpectedly found to satisfactorily solve the problem of resisting excessively high combustion chamber temperatures. In fact, the present liner has withstood operating temperatures of 3000° F. without failure. The stainless steel liner 132 serves not only to rapidly transfer heat therefrom to the water wall section 37 to thereby avoid excessive overheating of said liner, but transfers enough heat to the coil 37 to prevent condensation of liquid fuels and moisture thereon.

A further advantage of the sheet metal liner 132 and water wall arrangement 37 disclosed herein is that it greatly outlasts refractory walls, but what is more important, makes it possible to make the unit more compact by not occupying anywhere near as great a space as would normally be required for the thickness of refractory material necessary to withstand the same combustion chamber temperatures.

It is important to make the metal liner 132 of a dimension that will allow the liner to expand and make positive contact with the turns of the water wall 37 upon thermal expansion thereof. If insufficient clearance for expansion is allowed, the liner 132 will buckle upon expansion and burn or scale at the buckled points. On the other hand, if too much clearance is provided, the liner will not expand into heat-transferring contact with the water wall 37 and burn or scale because of improper cooling thereof.

Insofar as the operation of the heating coil itself is concerned, the liquid to be heated is introduced through the inlet 39 into the preheater section 36 so that the liquid is preheated before it enters the water wall section 37. Hence, too low temperatures in the water wall section 37 are avoided, and this eliminates condensation of

8
fuel vapor which would cause carbon deposits. It also eliminates collection of and condensation of moisture from the air on the external surface of the water wall tubing, which would result in active corrosion. The water wall section 37, as previously explained, is double wound so that the fluid flows downwardly in the water wall section in the helical coil portion formed by the pipe 50 and upwardly in the water wall section 37 through the helical coil portion formed by the pipe 51, to be discharged into the uppermost pancake coil 60 of the generating section 38. The fluid passes through the first pancake coil 60 of the generating section 38 and then directly to the bottom pancake coil 60, and at this point changes from counterflow to direct flow and passes upwardly through the balance of the pancake coils 60 and is then discharged through the riser pipe 11 into a steam separator (not shown) or any other apparatus.

The upper turns of the water wall section 37 are arranged closely adjacent each other for the purpose of providing a combustion gas seal at the critical point or level of the combustion chamber 20, whereas, the lowermost turns of the water wall section 37 are spaced apart to facilitate absorption of the radiant heat of the liner 132, the surface of the water wall coils 37 directly in contact with the liner 132, of course, absorbing heat by direct conduction. The vertical spacing or pitch of the lower coils of the water wall section 37 is such that sufficient heat transfer will be effected by direct conduction and radiation to maintain the liner 132 sufficiently cool to prevent overheating or burning out of the same.

40 The double wound water wall 37 provides a return pass for the fluid without requiring the necessity of employing any external piping or tubing. At the same time, the flow of the fluid through the water wall section 37 results in the absorption of heat from the combustion chamber and from the liner 132 so that the fluid is discharged into the generating section 38 at a slightly elevated temperature above that at which it entered the water wall section 37.

45 The object of connecting the upper pancake coil 60 of the generating section 38 to the lower pancake coil of said section is to provide a construction in which some fluid is always present in the pancake coil 60 nearest to the combustion chamber 20, but which fluid is not at the maximum temperature to which the unit is capable of heating the same. In other words, additional heat is absorbed in the generating section 38 by the fluid as it travels in a generally upward direction through the generating section 38. The principal advantage of such an arrangement is that excessive temperatures in the lowermost pancake coil 60 are avoided. The arrangement also creates a higher temperature differential between the temperature of the fluid in the coil and the temperature of the combustion gases, which increases the effectiveness of the heating coil. In fact, thermal efficiencies as high as 82% are commonly attained in units embodying the coil assembly 35.

50 The present coil construction not only makes it possible to develop a given boiler horsepower with less heating surface than previous units designed to develop the same boiler horsepower, but has also resulted in a reduction in the feed pump pressure required to force the feed water into the coil. For example, previous 50 horsepower units supplying steam at a pressure of 100 lbs. per square inch have required a feed pump

pressure of 280 to 290 lbs. per square inch as compared with a feed water pump pressure of 260 lbs. per square inch for the present unit. This indicates that less actual steam or vapor was formed in the heating coil 35 with a greater proportion of solid liquid than vapor, which resulted in less friction flow loss through said coil. In practice, it is desired to maintain a stream of fluid flowing through the heating coil 35 containing a maximum ratio of 25% vapor to 75% liquid. In other words, the reduction in the back pressure indicates that a greater percentage of heat is absorbed by the liquid and only a comparatively small amount of the liquid is converted to vapor during the passage of liquid through the heating coil before it discharges from the outlet pipe 71 into a steam separator or other apparatus (not shown).

While the heating coil, combustion chamber lining means, and the means for maintaining a low jacket temperature have been described in connection with a steam generating apparatus, it is to be understood that the invention is not limited to the use of these features in apparatus for generating steam, and that the invention contemplates their use wherever susceptible.

It will be understood that various changes may be made in the materials and details of construction of the apparatus disclosed herein, without departing from the spirit of the invention or the scope of the annexed claims.

I claim:

1. Steam generating apparatus, comprising: a shell; a coil in said shell including a plurality of superposed vertically spaced helical turns; and a cylindrical chrome-nickel steel liner within said heating coil, said liner having a thickness in the range of .04" to .14" and initially fitting within said coil with a slight clearance but being thermally expansible into positive heat transfer engagement with the inner periphery of the turns of said coil upon heating thereof.

2. Steam generating apparatus, comprising: a shell; a combustion chamber within said shell; means at the lower end of said shell forming a bottom wall for said combustion chamber; a coil within said shell including a plurality of superposed, vertically spaced helical turns; and an 18-8 chrome-nickel steel sheet liner within said coil, said liner having a thickness of .04" to .14" and initially fitting within said coil with a slight clearance but being thermally expansible into positive heat transfer engagement with said coil upon heating thereof, the lower end of said liner resting upon said bottom wall of said combustion chamber.

3. Steam generating apparatus, comprising: a shell; a combustion chamber within said shell; means at the lower end of said shell forming a bottom wall for said combustion chamber; a coil within said shell including superposed helical turns with the turns at the upper end of said coil arranged close together and the turns at the lower end of said coil spaced apart a predetermined distance; and a cylindrical, chrome-nickel steel sheet metal liner within the lower portion of said coil initially fitting within said coil with a slight clearance but being thermally expansible into positive heat transfer engagement with the inner periphery of the turns of said coil upon heating thereof, said liner extending throughout the height of said spaced apart turns with the lower end of said liner resting upon said bottom wall of said combustion chamber.

4. Steam generating apparatus, comprising: a

base including two substantially horizontal, circular walls spaced apart to provide an air space therebetween, the upper of said walls being smaller in diameter than the lower of said walls; a pair of spaced apart concentric ring members having an air space disposed therebetween and having their lower ends connected with the periphery of said spaced horizontal walls to form an annular continuation of the air space between said horizontal walls; means for forcing air under pressure into the central portion of the air space between said horizontal walls; means interposed between said horizontal walls for deflecting the air, thus introduced, outwardly into said annular air space between said concentric rings; a housing disposed above said base including a shell having insulating material surrounding the same; a jacket lined with insulating material surrounding said shell, with an annular air space between said shell insulating material and said jacket insulating material; and means between said base and housing establishing communication between said annular air space in said base and said annular air space in said housing.

5. Steam generating apparatus, comprising: a shell; a heating coil within said shell; a sheet metal liner within said heating coil, said liner initially fitting within said coil with a slight clearance but being thermally expansible into positive heat transfer engagement with said coil upon heating thereof; heat insulating material surrounding the exterior of said shell; a jacket surrounding said heat insulating material; a liner of heat insulating material lining said jacket and being separated from said first-mentioned heat insulating material by an annular air space; a base at the lower end of said shell and jacket, the lower end of said liner resting upon said base and cooperating therewith to provide a combustion chamber, said base including a double wall with an air space therebetween communicating with said annular air space; and means for forcing air under pressure into said combustion chamber, and into the air space between said double walls of said base and thence into said annular air space.

6. Steam generating apparatus, comprising: a jacket; a shell within said jacket; an annular air space between said shell and jacket; a coil within said shell; a sheet metal liner within said coil, said liner initially fitting within said coil with a slight clearance but being thermally expansible into positive heat transfer engagement with said coil upon heating thereof; a base member below said jacket, shell, coil and liner and including a bottom wall; refractory material supported by said bottom wall, the lower end of said liner resting upon said refractory material and cooperating therewith to provide a combustion chamber; a second bottom wall disposed below said first bottom wall to provide an air space between said two bottom walls; means establishing communication between said annular air space and said air space between said bottom walls, each of said bottom walls having an opening communicating with said combustion chamber; burner means aligned with said openings; and means for forcing air under pressure into the opening in said second bottom wall.

7. Steam generating apparatus, comprising: a jacket; a shell within said jacket; an annular air space between said shell and jacket; a coil within said shell; a sheet metal liner within said coil, said liner initially fitting within said coil with a slight clearance but being thermally ex-

pansible into positive heat transfer engagement with said coil upon heating thereof; a base member below said jacket, shell, coil and liner and including a bottom wall; refractory material supported by said bottom wall and cooperating with said liner to provide a combustion chamber; a second bottom wall disposed below said first bottom wall to provide an air space between said two bottom walls; means establishing communication between said annular air space and said air space between said bottom walls, each of said bottom walls having an opening communicating with said combustion chamber, the opening in the first bottom wall being smaller than the opening in the second bottom wall to effect deflection of air into the space between said bottom walls; burner means aligned with said openings; and means for forcing air under pressure into the opening in said second bottom wall.

8. Steam generating apparatus, comprising: a jacket; a shell within said jacket; an annular air space between said shell and jacket; a coil within said shell; a sheet metal liner within said coil, said liner initially fitting within said coil with a slight clearance but being thermally expansible into positive heat transfer engagement with said coil upon heating thereof; a base member below said jacket, shell, coil and liner and including a bottom wall; refractory material supported by said bottom wall, said liner cooperating with said bottom wall to provide a combustion chamber; a second bottom wall disposed below said first bottom wall to provide an air space between said two bottom walls; means establishing communication between said annular air space and said air space between said bottom walls, each of said bottom walls having an opening communicating with said combustion chamber, the opening in the first bottom wall being smaller than the opening in the second bottom wall to effect deflection of air into the space between said bottom walls; burner means aligned with said openings; means for forcing air under pressure into the opening in said second bottom wall; and baffle members in the air space between said bottom walls extending outwardly from a point adjacent said openings in said bottom walls.

9. Steam generating apparatus, comprising: a jacket; a shell within said jacket; an annular air space between said shell and jacket; a coil within said shell; a sheet metal liner within said coil, said liner initially fitting within said coil with a slight clearance but being thermally expansible into positive heat transfer engagement with said coil upon heating thereof; a base below said jacket, shell, coil and liner, the lower end of said liner resting upon said base and cooperating therewith to provide a combustion chamber, said base including two substantially horizontal, circular bottom walls spaced apart to provide an air space therebetween, the upper of said walls being smaller in diameter than the lower of said walls and both of said walls having an air inlet opening; a pair of concentric rings having an air space formed therebetween and having their lower ends connected with the periphery of said spaced bottom walls to form an annular continuation of the air space between said horizontal walls, the annular air space of said base being aligned with the annular air space between said jacket and shell; a transverse wall separating said annular air spaces, said transverse wall having apertures establishing communication between said annular air spaces; and means for forcing air under pressure into said combustion

chamber and the air space between said bottom walls through the air inlet openings in said bottom walls.

10. Steam generating apparatus, comprising: 5 a base including two substantially horizontal, circular walls spaced apart to provide an air space therebetween, the upper of said walls being smaller in diameter than the lower of said walls; a pair of concentric rings having an air space 10 formed therebetween and having their lower ends connected with the periphery of said spaced bottom walls to form an annular continuation of the air space between said horizontal walls; a housing disposed above said base member including a shell having insulating material surrounding the same; a jacket lined with insulating material, with an annular air space between said shell insulating material and said jacket insulating material; means establishing communication 15 between said annular air space in said base and said annular air space in said housing; a helically wound heating coil within said shell above said base; a plurality of supporting elements positioned in said base in the annular air space between said concentric rings; and feet members secured to the lower turn of said helical coil and resting upon said supporting elements, said feet members varying in vertical height to support said coil perpendicularly relative to said base.

11. Steam generating apparatus as defined in claim 10, including a liner disposed within said heating coil and having its lower end supported by the base.

12. Steam generating apparatus as defined in claim 10, including means for forcing air into the base in the space between the circular walls thereof, and baffle means in said space for deflecting the air outwardly into the annular space 40 between the concentric rings, for flow upwardly through the annular space in the housing.

13. Steam generating apparatus, comprising: a base member; a plurality of radially extending inverted U-shaped supporting members carried 45 by said base; a substantially cylindrical shell having its lower edge resting upon said supporting members; a body of refractory material supported by said base and disposed inwardly of said supporting members; bracket means carried by 50 said shell member at a region adjacent to but spaced from the lower end thereof; a leg having a flange extending inwardly at a point below said base; and bolt means extending through said bracket means, one of said U-shaped supporting members, base and flange of said leg and securing said shell, base and leg in assembled relation.
